UNITED STATES PATENT OFFICE.

THOMAS E. BART, OF CINCINNATI, OHIO, ASSIGNOR TO THE MURDOCK MANUFACTURING AND SUPPLY COMPANY, OF CINCINNATI, OHIO, A CORPORATION OF OHIO.

RAILWAY WATER-SERVICE DEVICE.

Application filed May 3, 1921. Serial No. 466,607.

To all whom it may concern:

Be it known that I, THOMAS E. BART, a citizen of the United States of America, and a resident of Cincinnati, in the county of Hamilton and State of Ohio, have invented a new and useful Improvement in a Railway Water-Service Device, of which the following is a specification.

The devices used in railway yards, wherewith coaches are supplied with water, are subject to vibration caused by the movement of trains adjacent thereto, wherefore after a short period of use the valves employed in these devices open because of such vibration and water escapes or leaks from these devices. The water escaping from these devices generally soaks the ground adjacent thereto, because generally there is provided no adequate drain for this escaping water. This water freezes in the winter and in the summer causes a soggy, muddy, infirm footing, both of which increase the dangers and hazard accompanying the work about the railroads. Due to the construction of these devices, they extend to a considerable distance above the surface of the ground adjacent, and are therefore menaces to the safety of those working about the yards and about the trains. The lids upon these devices are often times left in a raised position through careless employees, thereby subjecting the mechanism to cinders and dirt, which are detrimental to the proper functioning of the devices, and the raised lids of which are further menaces to the safety of those working thereabout. These devices are all more or less subject to freezing, and as a result parts thereof are broken and the device becomes inoperative. An object of my invention is to provide a device for the purposes stated that will afford a maximum of safety to those exposed thereto in that the causes of danger set forth above are eliminated by my device.

Another object of my invention is to provide a device especially adaptable for use in and about railway yards wherein the valve controlling the flow of water therethrough will be self closing and which will withstand the vibration caused by the trains.

Another object of my invention is to provide a device that may be disposed in such position that the lid thereon will, when in a closed position, assume a position flush with the surface of the adjoining ground.

Another object is to provide a device having a self closing lid.

Another object is to provide a device wherein the box housing the parts of the device exposed to employees, will afford a minimum of danger to the persons obliged to work thereabouts, and a maximum of protection and safety to the parts of the device itself.

Another object is to provide a device for the purposes stated that will be anti-freezing and self draining, and in which the drain water from the water supply will be reduced to a minimum, thereby eliminating the wet, soggy areas now common about the devices being used at the present time where no adequate sewerage connections are installed.

These and other objects are attained by the means described herein and disclosed in the accompanying drawings, in which

Fig. 1 is a sectional side elevation of a device embodying my invention.

Fig. 2 is an enlarged sectional view of some of the parts shown in Fig. 1.

Fig. 3 is a sectional view on line 3-3 of Fig. 1.

Fig. 4 is an enlarged sectional view on line 4-4 of Fig. 3.

My invention comprises a box A adapted to be sunk in the ground and having its top flush with the ground E. A casing a¹ extends downwardly into the ground from the box and contains a valve b¹² controlling the flow of water through the supply pipe B terminating in the box. A suitable lever a¹⁵ is provided in the box for operating the valve. Normally the valve is retained upon its seat by means of a spring b⁸.

The box A has a lid a pivotally mounted upon one side thereof adjacent the top thereof by means of the pivots a'. A lug a² is formed upon the end of the lid adjacent the pivots a' and the lug has an angular face a³ adapted to be moved into engagement with the outer wall a⁴ of the box when the lid is lifted or raised. This face a³ is disposed at

such an angle so as to preclude raising of the lid to a vertical position or at right angles in relation to the top a^5 of the box, wherefore the lid will always be returned to its seat upon the box by the action of gravity when the force moving the lid about its pivots a^4 is withdrawn. A flange a^6 is formed upon the bottom of the box and has mounted upon it a casing a^7 . A supply pipe 10 B extends through the casing and through the flange a^6 terminating in the lever chamber a^8 in the box A. A collar a^9 is mounted within the chamber a^8 upon the bottom of the box A, and the supply pipe B extends reciprocally through the collar. A shoulder a^{10} is formed upon the collar adjacent the supply pipe. The collar a^9 is mounted upon the box A by suitable bolts a^{11} and a standard a^{12} having a screw a^{13} formed upon its lower end, whereby the standard is mounted upon the bottom of the box A and serves also to bind the collar upon the box A. The upper end a^{14} of the standard is bifurcated. A hand lever a^{15} , having an elongated slot a^{16} 20 in one of its ends, is pivotally mounted between the bifurcated end of the standard a^{12} by means of a pivot a^{17} extending through the slot in the lever. The other end of the lever has a suitable handle a^{18} whereby the lever may be moved about the pivot a^{17} . A lug a^{19} is formed on the lever adjacent to and immediately below the handle a^{18} , and is adapted to engage a lug a^{20} formed upon the interior of the box A and to thereby retain the lever in a raised position. Sufficient play is provided between the branches of the standard and the slotted end of the lever a^{15} to permit lateral motion of the handle of the hand lever. A drain flange a^{21} is provided in the bottom of the box A and the bottom a^{22} of the box is inclined so that any surface water that may enter the box will escape therefrom by way of the drain a^{21} .

The supply pipe B has mounted upon its upper end a discharge head b having bifurcated water passages b^1 and b^2 therethrough, thereby providing a slot b^3 through the discharge head. The walls of the slot b^3 are curved so that the narrowest portion of the slot is formed at substantially the center of the slot. The lever a^{15} extends through the slot b^3 , thereby mounting the discharge head intermediate the ends of the lever. The upper end b^4 of the discharge head is screw 40 threaded, whereby a suitable pipe or hose C may be attached thereto. An apron b^5 is formed about the lower end of the discharge head and is adapted to extend over the shoulder a^{10} formed on the flange a^6 which shoulder terminates adjacent shoulder b^6 on the head. This structure precludes the passage of surface water through the flange a^6 . A collar b^7 is mounted upon the supply pipe B and is contained within the casing a^7 . A 50 spring b^8 abuts the collar b^7 and the flange

a^6 , and normally tends to move the supply pipe B longitudinally downward through the casing a^7 . A housing b^9 is mounted upon the lower end of the supply pipe B and has formed within it a valve chamber b^{10} within which is disposed a spider b^{11} upon which is mounted a suitable valve b^{12} formed of any material such as leather, and retained in position by any suitable means such as a screw b^{13} . The lower end of the housing b^9 extends about a supply nozzle b^{14} , and may be longitudinally reciprocated thereover. A flange b^{15} is formed within the housing b^9 adjacent its lower end and provides a seat against which suitable washers or packing rings b^{16} may be retained by means of a screw b^{17} adapted to be mounted upon the lower end of the housing. The nozzle b^{14} extends slidably through the screw b^{17} and the flange b^{15} . A by-pass or channel b^{18} is formed in the outer wall of the nozzle b^{14} in such position that when the housing b^9 assumes its lowermost or normal position, any water contained within the valve chamber b^{10} may drain from the chamber by way of the by-pass. When the housing b^9 is raised so as to lift the valve b^{12} from the valve seat b^{19} formed upon the upper end of the nozzle b^{14} , the washers b^{16} assume a position above the by-pass b^{18} and preclude the escape of water from the chamber b^{10} by way of the channel b^{18} . A drain cap D is mounted upon the lower end of the casing a^7 . Any suitable drain cap may be employed for this purpose, but it is preferable to employ a cap such as is disclosed in the application of Kelso Murdock, Serial No. 363,619, and assigned to the Murdock Manufacturing and Supply Company. The discharge nozzle b^{14} is connected with a suitable water supply by means of the pipe d and the channel d' provided within the drain cap D, the upper end of which channel communicates with the interior of the nozzle b^{14} . This communication may be provided in any suitable manner such as by mounting the nozzle upon the spider d^2 formed within the drain cap and supporting the upper end of the wall d^3 defining the channel d' through the cap D.

The operation of my device is as follows:

Normally the spring b^8 retains the valve b^{12} upon its seat b^{19} , wherefore it is normally possible for any water within the valve chamber b^{10} , the supply pipe B and the discharge head b, to escape from the said compartments by way of the channel b^{18} . When the parts are in this normal relation, the lug a^{19} on the lever a^{15} is disengaged from the lug a^{20} formed within the box. When it is desired to withdraw water from the pipe d, a suitable hose such as C is attached to the upper end of the discharge head b, and the handle a^{18} is lifted so that the lug a^{19} thereupon will be raised above the lug

a^{20} on the box, thereby lifting the valve b^{12} from its seat b^{10} . The rounded walls of the slot extending through the discharge head permits the supply pipe B to be moved longitudinally without being moved laterally. If it is desired that a continuous flow be secured from the device, the handle a^{18} is moved laterally until the lug a^{19} assumes a position over a notch a^{23} formed upon the top of the lug a^{20} , and the handle is then released. The supply pipe B is capable of rotatory motion to accommodate the lateral movement of the handle. The contact of the lugs a^{19} and a^{20} serve to retain the valve upon its seat against the yielding pressure of the spring b^8 . When the parts are in this position the washers b^{16} have been moved to a position above the channel b^{18} , thereby precluding the escape of any water from the valve chamber b^{10} through any path other than that through the supply pipe B. When the handle is disengaged from the lug a^{20} and is then released, the spring b^8 returns the parts to their normal positions, wherein the valve engages its seat shutting off the flow of water, and the washers b^{16} assume a position substantially mid-way of the ends of the channel b^{18} , wherefore the water within and above the valve chamber b^{10} drains through the channel b^{18} and escapes from the bottom of the housing by way of the drain cap D.

From the foregoing it is readily apparent that there will be very little drain water resulting from the use of this device, wherefore this drain water will be readily absorbed by the ground about the drain cap D. The amount of water that will find its way into the box will be very small in volume and a suitable drain, not shown, is provided to carry this surface water from the box.

What I claim is:

1. A water service device comprising the combination of a box, the top of which is adapted to be mounted flush with the surface of adjoining ground, a casing extending downwardly from the box, a supply pipe mounted reciprocally in the casing and extending into the box, a lever within the box engaging the supply pipe and adapted to move the supply pipe in the direction of its length, a supply nozzle contained within the casing communicating with a water supply adapted to direct a flow of water to the supply pipe, a valve mounted on the supply pipe adapted to seal the supply nozzle, and means yieldably retaining the valve in engagement upon the supply nozzle.

2. A water service device comprising the combination of a supply nozzle, a revolvable supply pipe communicating with the supply nozzle, a valve mounted on the supply pipe adapted to seal the supply nozzle, a lever engaging the supply pipe adapted to

move the supply pipe longitudinally and to rotatably actuate the supply pipe, and a lug adjacent the lever, the longitudinal movement of the supply pipe serving to engage and disengage the valve upon the supply nozzle and the rotatory motion of the supply pipe permitting engagement of the lever and the lug whereby the valve may be retained out of engagement with the supply nozzle.

3. A water service device comprising the combination of a supply nozzle, a revolvable supply pipe communicating with the supply nozzle, a valve mounted on the supply pipe adapted to seal the supply nozzle, a lever engaging the supply pipe adapted to move the supply pipe longitudinally and to rotatably actuate the supply pipe, a lug adjacent the lever, the longitudinal movement of the supply pipe serving to engage and disengage the valve upon the supply nozzle and the rotatory motion of the supply pipe permitting engagement of the lever and the lug whereby the valve may be retained out of engagement with the supply nozzle, and means yieldably retaining the valve in engagement with its seat.

4. A water service device comprising the combination of a box, the top of which is adapted to be mounted flush with the surface of the adjoining ground, a self closing lid for the box, a casing extending downwardly from the box, a supply pipe in the casing extending into the box, a supply nozzle adapted to communicate with the end of the supply pipe disposed within the casing, a valve controlling communication between the supply nozzle and the supply pipe, the end of the supply pipe within the box being adapted to engage a hose, and means within the box for actuating the valve.

5. A water service device comprising the combination of a box, the top of which is adapted to be mounted flush with the surface of the adjoining ground, a self closing lid for the box, a casing extending downwardly from the box, a supply pipe in the casing extending into the box, a supply nozzle adapted to communicate with the end of the supply pipe disposed within the casing, a valve controlling communication between the supply nozzle and the supply pipe, the end of the supply pipe within the box being adapted to engage a hose, means within the box for actuating the valve, and yieldable means normally retaining the valve upon its seat.

6. A water service device comprising the combination of a box, the top of which is adapted to be mounted flush with the surface of the adjoining ground, a self closing lid for the box, a casing extending downwardly from the box, a supply pipe in the casing extending into the box, a discharge head in the box mounted upon the upper end of the

supply pipe, a supply nozzle in the casing having a drain channel formed in its outer wall, a housing mounted on the lower end of the supply pipe into which the nozzle extends, a washer mounted on the housing adapted to be moved to a position intermediate the ends of the drain channel and to a position beyond the drain channel, a valve in the housing adapted to seal the supply nozzle, a drain cap upon the bottom of the casing, a lever in the box adapted to actuate the supply pipe in the direction of its length, whereby the valve may be moved from its seat simultaneously with the movement of the washer beyond the drain channel, and means yieldingly retaining the valve on its seat and the washer intermediate the ends of the drain channel.

7. A water service device comprising the combination of a box, the top of which is adapted to be disposed flush with the adjacent ground and having a drain port in its bottom, a downwardly projecting flange formed upon the bottom of the box having a bore therethrough, a collar mounted upon the bottom of the box extending over the bore in the flange and having a bore in alignment with the bore in the flange, an upwardly projecting shoulder formed on the collar, a downwardly extending casing mounted upon the flange, a supply pipe extending reciprocally through the flange and the collar, a discharge head having a bifurcated water passage therethrough and a slot having rounded walls extending between the branches of the water passage mounted upon the supply pipe and contained within the box, an apron mounted upon the discharge head extending over the shoulder on the collar and forming therewith a wafer seal, a bifurcated standard mounted within the box, a lever extending through the slot in the discharge head and having an elongated slot in one end, a pivot extending through the slot in the lever and mounting the lever upon the branches of the standard, the pivot, the lever and the branches of the standard bearing such relation that the free end of the lever may be actuated laterally, a lug within the box adapted to be engaged by the free end of the lever, a supply nozzle within the casing adapted to communicate with the supply pipe, a valve mounted on the supply pipe controlling communication between the supply nozzle and the supply pipe, a spring disposed within the casing adapted to yieldingly retain the valve in engagement with its seat, the lever being adapted to actuate the supply pipe in the direction of its length, whereby the valve may be moved from its seat and to revolvably actuate the supply pipe whereby the free end of the lever may be moved into engagement with the lug in the box when the valve is unseated, whereby a continuous flow through the discharge head may be provided.

8. A water service device comprising the combination of a box, the top of which is adapted to be disposed flush with the adjacent ground and having a drain port in its bottom, a downwardly projecting flange formed upon the bottom of the box having a bore therethrough, a collar mounted upon the bottom of the box extending over the bore in the flange and having a bore in alignment with the bore in the flange, an upwardly projecting shoulder formed on the collar, a downwardly extending casing mounted upon the flange, a supply pipe extending reciprocally through the flange and the collar, a discharge head having a bifurcated water passage therethrough and a slot having rounded walls extending between the branches of the water passage mounted upon the supply pipe and contained within the box, an apron mounted upon the discharge head extending over the shoulder on the collar and forming therewith a wafer seal, a bifurcated standard mounted within the box, a lever extending through the slot in the discharge head and having an elongated slot in one end, a pivot extending through the slot in the lever and mounting the lever upon the branches of the standard, the pivot, the lever and the branches of the standard bearing such relation that the free end of the lever may be actuated laterally, a lug within the box adapted to be engaged by the free end of the lever, a supply nozzle within the casing adapted to communicate with the supply pipe, a valve mounted on the supply pipe controlling communication between the supply nozzle and the supply pipe, a spring disposed within the casing adapted to yieldingly retain the valve in engagement with its seat, the lever being adapted to actuate the supply pipe in the direction of its length, whereby the valve may be moved from its seat, and to revolvably actuate the supply pipe whereby the free end of the lever may be moved into engagement with the lug in the box when the valve is unseated, whereby a continuous flow through the discharge head may be provided, and a self closing lid for the box.

9. A water service device comprising the combination of a box, the top of which is adapted to be disposed flush with the adjacent ground and having a drain port in its bottom, a downwardly projecting flange formed upon the bottom of the box having a bore therethrough, a collar mounted upon the bottom of the box extending over the bore in the flange and having a bore in alignment with the bore in the flange, an upwardly projecting shoulder formed on the collar, a downwardly extending casing mounted upon the flange, a supply pipe extending reciprocally through the flange and

the collar, a discharge head having a bifurcated passage therethrough and a slot having rounded walls extending between the branches of the water passage mounted upon 5 the supply pipe and contained within the box, an apron mounted upon the discharge head extending over the shoulder on the collar and forming therewith a water seal, a bifurcated standard mounted within the 10 box, a lever extending through the slot in the discharge head and having an elongated slot in one end, a pivot extending through the slot and the lever and mounting the lever upon the branches of the standard, the 15 pivot, the lever and the branches of the standard bearing such relation that the free end of the lever may be actuated laterally, a lug within the box adapted to be engaged by the free end of the lever, a supply nozzle 20 within the casing and having a drain channel in its outer wall, a housing mounted upon the supply pipe having a valve chamber therein and into which chamber the nozzle reciprocally extends, a valve within 25 the valve chamber adapted to seal the supply nozzle, washers mounted on the housing adapted to assume a position intermediate the ends of the drain channel and a position beyond the drain channel, a spring 30 yieldingly retaining the valve in engagement upon its seat, the lever being adapted to move the supply pipe in the direction of its length whereby the valve is moved from its seat and the washer assumes a position beyond the ends of the channel, and to 35 revolvably actuate the supply pipe whereby the lever may be moved into engagement with the lug in the box when in its raised position, whereby a continuous flow through the supply pipe is attained, and means to 40 drain the casing.

10. A water service device comprising the combination of a box, the top of which is adapted to be mounted flush with the surface of adjoining ground, a casing extending downwardly from the box, a supply pipe mounted reciprocally in the casing and extending into the box, means within the box 45 for moving the supply pipe in the direction of its length, a supply nozzle contained within the casing communicating with a fluid supply adapted to direct a flow of fluid to the supply pipe, a valve mounted on the supply pipe adapted to seal the supply nozzle, and means yieldingly retaining the valve in engagement upon the supply nozzle.

11. A water service device comprising the combination of a box, the top of which is adapted to be mounted flush with the surface of adjoining ground, a casing extending downwardly from the box, a supply pipe mounted reciprocally in the casing and extending into the box, means within the box 50 for moving the supply pipe in the direction of its length, a supply nozzle contained

within the casing communicating with a fluid supply adapted to direct a flow of fluid to the supply pipe, a valve mounted on the supply pipe adapted to seal the supply nozzle, means yieldingly retaining the valve in engagement upon the supply nozzle, and a self closing lid for the box controlling access to the supply pipe and moving means therefor. 70

12. A water service device comprising the combination of a box, the top of which is adapted to be mounted flush with the surface of adjoining ground, a casing extending downwardly from the box, a supply pipe mounted reciprocally in the casing and extending into the box, means within the box 75 for moving the supply pipe in the direction of its length, a supply nozzle contained within the casing communicating with a fluid supply adapted to direct a flow of fluid to the supply pipe, a valve mounted on the supply pipe adapted to seal the supply nozzle, means yieldingly retaining the valve in engagement upon the supply nozzle, and means for retaining the valve out of engagement with the supply nozzle. 80

13. A water service device comprising the combination of a supply nozzle, a revoluble and reciprocable supply pipe communicating with the supply nozzle, a valve mounted on the supply pipe adapted to seal the supply nozzle, means yieldingly retaining the valve in engagement upon the supply nozzle, and means to retain the valve out of engagement with the supply nozzle, the reciprocable movement of the supply pipe serving to engage and disengage the valve and supply nozzle, and the rotatory movement of the supply pipe serving to render the last mentioned means operative whereby the 105 valve and supply pipe may be retained out of engagement. 100

14. A water service device comprising the combination of a box having a supply pipe opening and a drain opening, a supply pipe 110 extending thru the supply pipe opening, a shoulder carried by the box surrounding the supply pipe and extending above the drain opening, and an apron carried by the supply pipe extending downwardly about the shoulder and with the shoulder forming a water seal, whereby the box may be drained at all times and water is precluded from entering the supply pipe opening. 115

15. A water service device comprising the combination of a box having a supply pipe opening and a drain opening, a supply pipe extending thru the supply pipe opening, a shoulder carried by the box surrounding the supply pipe and extending above the drain 120 opening, and an apron carried by the supply pipe extending downwardly about the shoulder and with the shoulder forming a water seal, whereby the box may be drained at all times and water is precluded from entering 125. 130

the supply pipe opening, and a self closing lid for the box controlling access to the supply pipe.

16. A water service device comprising the combination of a supply nozzle, a revoluble supply pipe communicating with the supply nozzle, a valve mounted on the supply pipe adapted to seal the supply nozzle, a lever engaging the supply pipe adapted to move the supply pipe longitudinally and to rotatably actuate the supply pipe, a lug adjacent the lever, the longitudinal movement of the supply pipe serving to engage and disengage the valve upon the supply nozzle and the rotatory motion of the supply pipe permitting engagement of the lever and the lug whereby the valve may be retained out of engagement with the supply nozzle, and a drain cap at the base of the casing.

17. A water service device comprising the combination of a box, the top of which is adapted to be mounted flush with the surface of the adjoining ground, a casing ex-

tending downwardly from the box, a supply pipe in the casing extending into the box, a supply nozzle in the casing having a drain channel formed in its outer wall, a housing mounted on the lower end of the supply pipe into which the nozzle extends, a washer mounted on the housing adapted to be moved to a position intermediate the ends of the drain channel and to a position beyond the drain channel, a valve in the housing adapted to seal the supply nozzle, a drain cap upon the bottom of the casing, a lever in the box adapted to actuate the supply pipe in the direction of its length, whereby the valve may be moved from its seat simultaneously with the movement of the washer beyond the drain channel, and means yieldingly retaining the valve on its seat and the washer intermediate the ends of the drain channel.

In testimony whereof, I have hereunto subscribed my name this 30th day of April, 1921.

THOMAS E. BART.
